Patented June 23, 1925.

UNITED STATES PATENT OFFICE.

GUSTAVE LIDSEEN, OF CHICAGO, ILLINOIS.

PUMP-FEED OIL CAN.

Application filed December 1, 1924. Serial No. 753,234.

To all whom it may concern:

Be it known that I, GUSTAVE LIDSEEN, a citizen of the United States, and a resident of the city of Chicago, in the county of Cook and State of Illinois, have invented certain new and useful Improvements in a Pump-Feed Oil Can; and I hereby declare that the following is a full, clear, and exact description of the same, reference being had to the accompanying drawings, and to the numerals of reference marked thereon, which form a part of this specification.

This invention relates to an improved type of oil can wherein the spout cover has a lever mechanism supported thereon in position to operate a chambered piston or plunger, said plunger having rigidly secured thereto an angled stem or oil feed pipe which is adapted to be moved with said plunger when the lever is operated to cause oil to be pumped into a sleeve and out through a spring controlled valve into the oil can spout for distribution.

It is an object of this invention to provide a simple feed oil can wherein an oil feed pipe which projects into the can has the upper end thereof rigidly secured to a lever operated plunger for the purpose of permitting oil to be pumped from the oil can spout as desired.

It is also an object of this invention to provide an improved pump feed oil can wherein the oil can spout is provided with a sleeve or casing having a simplified form of outlet valve mounted thereon in position to be actuated by an oil pumping plunger having an oil feed tube formed thereon and projecting into the oil can with said plunger and oil feed pipe adapted to be simultaneously actuated against the resistance of a control spring by a lever mechanism supported on the oil can cover.

It is an important object of this invention to provide an improved oil can wherein an oil pump mechanism is supported on the oil can cover and embraces a lever operated plunger device to which one end of an angled oil feed pipe is rigidly secured with said oil feed pipe having an oil inlet valve positioned in the other end thereof near the bottom of the oil can to afford an effective lubricating device for use in cases where it is not necessary to tip or tilt the oil can downwardly beyond a horizontal position.

Other and further important objects of this invention will be apparent from the dis-

closures in the specification and the accompanying drawings.

This invention (in a preferred form) is illustrated in the drawings and hereinafter more fully described.

On the drawings:

Figure 1 is an elevational view of an improved pump feed oil can embodying the principles of this invention.

Figure 2 is an enlarged fragmentary vertical central section of the oil can with parts shown in elevation.

Figure 3 is an enlarged fragmentary bottom plan view of the oil can cover.

Figure 4 is a fragmentary detail section taken on the line 4—4 of Figure 3.

As shown on the drawings:

The reference numeral 1 indicates a metal body or container provided with an integral neck portion 2 on the upper marginal edge of which a pair of oppositely disposed segment shaped flanges are integrally formed. Frictionally engaged with the container flanges are the segment shaped flanges 3 of a cover 4. Integrally formed or rigidly secured to the middle portion of the cover 4 is a cylindrical housing or casing 5 the upper end of which terminates in a long oil discharge nozzle or spout 6.

Rigidly secured within the cover housing 5 is a sleeve 7 the lower end of which is open and projects into the cover 4 to a point substantially in the plane of the cover flanges 3. The upper end of the sleeve 7 is provided with an integral closure plate 8 having an aperture in the middle thereof with the margin of the metal forming said aperture struck upwardly to afford a circular conical valve seat 9 to receive an oil outlet control ball valve 10 as illustrated in Figure 4. The control ball valve 10 is resiliently held seated in position in the conical valve seat 9 by means of a light coiled control spring 11 the upper end of which is seated against the top of a U-shaped retaining strap or staple 12 the ends of the side arms of which are slightly bent inwardly and curved to afford the retaining tongues 13 adapted to be removably snapped over opposite portions of the conical valve seat 9 to hold the spring 11 and the valve ball 10 in position upon the sleeve 7.

Disposed within the sleeve 7 is a heavy coiled spring 14 the upper end of which is seated against the inner face of the top plate 8 of the sleeve 7. The lower end of the con-

trol spring 14 is seated in a chambered or hollow cup-shaped piston or plunger 15 the upper end of which is open and slidably projects into the lower open end of the sleeve 7. Integrally formed or rigidly secured to the closed bottom of the plunger 15 around a circular opening therein is the upper end of an oil feed pipe or stem 16 which is slightly bent at an angle at 17, 10 (Figure 2) so that the lower portion of said oil feed stem is inclined with respect to the axis of the container and has the lower end thereof positioned near the bottom of the container adjacent the lower portion of the front wall portion of the container as clearly illustrated in Figure 2. Removably engaged on the lower end of the oil feed stem 16 is a cap 18 having a ball valve 19 closing an oil intake opening provided in said cap.

20 For the purpose of operating the plunger 15 and the oil feed stem 16 a lever mechanism is provided on the oil can cover 4. Said cover 4 is provided with a concave socket or seat 20 to afford a fulcrum seat for a thumb operated lever constructed of a plurality of parts. The lever mechanism comprises a concave washer or bearing plate 21 which is seated for frictional sliding movement in the concave socket 20. Rigidly secured to the concave washer 21 is the lower curved end of a thumb lever 22. Integrally formed on the lower curved end of the lever 22 is a long lug or tongue 23 which projects through an opening in the washer 21 and through an aperture provided in the socket 20 of the oil can cover. The tongue 23 has the end thereof bent to rigidly engage around the crotch end 24 of a two-tined fork to hold said fork secured in position 30 below the can cover 4 with the ends of the fork tines 25 disposed on opposite sides of the upper end of the oil feed tube 16 and against the bottom of the plunger 15. Said plunger is held against the ends of said fork tines by the action of the spring 14 within the sleeve 7. The crotch end 24 of the two-tined fork is provided with a pair of integrally spaced lugs 26 (Figure 3) which are disposed on opposite sides of the tongue and seat against a curved washer or shield 27 which is frictionally positioned against the bottom of the cover socket 20 to close the slot or aperture therein as illustrated in Figure 4.

40 The container 1 is adapted to be filled with oil through the open top or neck thereof after which the cover 4 is adapted to be removably engaged on the container 1 with the cover flanges 3 frictionally engaging the flanges formed on the neck of the container. The cover 4 supports the nozzle or spout 6 and also supports the lever and pump mechanisms of the improved pump feed oil can. When the cover is in place on the container 50 1 the oil feed pipe 16 is positioned as illus-

trated in Figure 2 with the valve positioned in the lower front corner of the container. When it is desired to oil a bearing the oil can is carried by means of the handle 28 with the thumb of the hand carrying the oil can resting upon the outer end of the lever 22. The oil can is then tilted toward a horizontal position with the outlet snout of the nozzle 6 properly positioned at the bearing to be oiled. By operating the lever 22 toward the cover 4 the tines 25 are swung upwardly and having frictional sliding contact with the bottom of the plunger 15 cause said plunger to slide inwardly into the lower end of the sleeve 7 thereby compressing the control spring 14 and at the same time elevating the oil feed stem or pipe 16 within the container 1 with the upward movement of the plunger 15. Repeated operations of the lever 22 will therefore cause a pumping action to take place within the container so that oil from the container is drawn into the lower end of the oil feed pipe 16 around the ball valve 19 to fill the oil feed pipe and the chamber formed between the sleeve 7 and the plunger 15. It will thus be noted that when the lever 22 is operated the plunger will cause oil within the trap chamber to be forced against the ball valve 10 thereby moving the same into open position against the action of the spring 11 and permitting oil from the oil trap to be pumped out through the oil can nozzle or spout 6 into the joint or bearing to be lubricated.

55 It will be noted that this particular type of pump feed oil can is constructed more particularly for use when oiling bearings and joints which are so positioned that the oil can does not have to be tilted below a horizontal position or entirely inverted as ordinarily is the practice. With the can tilted into horizontal position or slightly above horizontal, all of the oil within the can may be pumped into the lower valve end of the oil feed stem 16 and out of the can nozzle.

60 The improved pump feed oil can of this invention is of simplified construction having a reduced number of parts affording an oil can of less expensive construction, simple of operation and with slight possibility of any of the operating parts getting out of operating order.

65 I am aware that many changes may be made and numerous details of construction may be varied through a wide range without departing from the principles of this invention, and I therefore do not purpose limiting the patent granted hereon, otherwise than necessitated by the prior art.

70 I claim as my invention:

75 1. A pump feed oil can comprising a container, a closure therefor having a spout supported thereon, a spring controlled

- plunger mounted for reciprocation in the lower end of said spout, an oil feed pipe rigidly secured to said plunger and extending downwardly into said container, a lever mechanism on said closure adapted to be operated to simultaneously reciprocate said plunger and said oil feed pipe, and check valves in said closure and said feed pipe.
2. A pump feed oil can comprising a container, a spout therefor, a plunger slidably mounted within said spout, a spring for controlling said plunger, an angled oil feed pipe rigidly secured to said plunger and projecting downwardly into said container, a lever mechanism supported on said spout and contacting said plunger to permit reciprocation of the plunger and said oil feed pipe when the lever is actuated, and control valves in said spout and said feed pipe.
3. An oil can of the class described comprising a container, a cover removably engaged thereon, a spout on said cover, a valve in said spout, a sleeve secured in said spout, a plunger slidably mounted in said sleeve, a control spring in said sleeve engaging said plunger to hold the same projected therefrom, an oil feed pipe rigidly secured to said plunger and extending downwardly into said container, a valve in said feed pipe, and a lever mechanism supported on said cover and contacting said plunger to permit reciprocation of the plunger and said oil feed pipe when the lever mechanism is operated.
4. A lubricating device of the class described comprising a container, a cover removably engaged thereon, a spout rigidly secured to said cover with the lower end of said spout of cylindrical form, a sleeve rigidly secured in the cylindrical end of said spout and having a valve seat at the upper end thereof, a ball valve seated in said valve seat, a strap removably engaged on said sleeve, a spring positioned in said strap for resiliently holding the ball seated in said valve seat, a plunger slidably mounted in the lower end of said sleeve, a spring positioned between the top of said sleeve and said plunger, an oil feed pipe rigidly secured to said plunger and extending downwardly into said container, a valve in said oil feed pipe, and a pivoted lever mechanism supported on said cover and contacting said plunger to permit the plunger together with said oil feed pipe to be reciprocated when said lever mechanism is operated.
5. The combination with an oil container, of a pump feed cover mechanism therefor, comprising a cover, a spout rigidly secured thereon, a sleeve secured in said spout, a control valve mechanism supported on said sleeve, a spring controlled plunger telescoping within said sleeve, an oil feed pipe secured to said plunger, a valve therein, and means on said cover for reciprocating the plunger and said oil feed pipe to pump oil from the container through said valve out of the cover spout.
6. The combination with an oil can, of a valve controlled spout thereon, a spring controlled plunger mounted in said spout, lever means for reciprocating said plunger, and a valve controlled oil feed pipe rigidly secured to said plunger to be reciprocated therewith.
7. A lubricating device comprising a container, a cover therefor, a spout on said cover, a sleeve secured in said spout having a valve seat formed on the upper end of said sleeve, a ball valve seated in said valve seat, a U-shaped retaining strap having the ends thereof formed to permit the strap to be resiliently sprung over the opposite side of said valve seat, and a spring in said strap for holding the ball valve seated in said valve seat.
8. A lubricating device comprising a container, a spout removably engaged thereon, a control valve therein, a plunger adapted to reciprocate in said spout, means for reciprocating said plunger, an oil feed pipe rigidly secured to said plunger to be reciprocated therewith, and a valve mechanism at one end of said oil feed pipe to control the flow of oil from said container into said feed pipe.
9. A pump feed lubricating device comprising a container, a spout removably engaged thereon, a sleeve secured in said spout, a control valve supported on said sleeve to control the flow of oil from said spout, a spring controlled plunger in said sleeve, an oil feed pipe having one end thereof rigidly secured to said plunger, a control valve in the other end of said oil feed pipe, a forked member having the tines thereof movably engaged with said plunger on opposite sides of said oil feed pipe, and a lever mechanism pivotally supported on said spout and connected with said forked member to actuate the same to cause reciprocation of the plunger and said oil feed pipe.
10. A pump feed lubricating device comprising a container, a spout therefor, a plunger in said spout, an angled oil feed pipe rigidly secured to said plunger with the lower end of said pipe directed into one of the corners of said container, and a lever mechanism for reciprocating said plunger and said oil feed pipe to cause oil to be pumped from the container out of said spout.
11. A pump feed oil can comprising a container, a spout removably secured thereon, a sleeve secured in said spout, a control valve supported on one end of said sleeve, a spring controlled plunger positioned to reciprocate in the other end of said sleeve, a valve controlled oil feed pipe in said container having the upper end thereof rigidly secured to said plunger, and a lever pivotally supported on said spout having the inner

end thereof engaged with said plunger to cause reciprocation of said plunger and said oil feed pipe when the outer end of said lever is operated.

5 12. An oil feed device comprising a container, a spout removably engaged thereon, a control valve therein, an oil feed mechanism in said container having a reciprocal engagement with said spout, and a lever 10 mechanism on said spout for reciprocating said oil feed mechanism to cause oil from said container to actuate the valve and be pumped out of said spout.

13. In an oil feed device of the class described the combination with a spout, of a valve therein, a reciprocating oil feed pipe, a valve therein, a plunger rigidly secured on one end of said pipe and having sliding engagement with said spout, and a lever 20 mechanism on said spout for causing reciprocation of said pipe and said plunger.

14. In a device of the class described the combination with an oil can cover, of a sleeve secured therein, a valve supported on 25 one end of said sleeve, a spring controlled

plunger slidable in the other end of said sleeve, an oil feed pipe having one end thereof rigidly secured to said plunger, and a control valve in the other end of said pipe.

15. An oil feed device of the class described comprising a container, a valve controlled spout removably engaged thereon, a spring controlled plunger slidably engaged in said spout, a valve controlled oil feed pipe rigidly secured to said plunger, a 30 forked member slidably contacting said plunger, a lever pivotally supported on said spout, and a tongue integrally formed on said lever formed to grip said forked member to permit the forked member to be 35 actuated by said lever to cause reciprocation of said plunger and said oil feed pipe with respect to said spout.

In testimony whereof I have hereunto subscribed my name in the presence of two 40 45 subscribing witnesses.

GUSTAVE LIDSEEN.
